(57) CLAIM

The ornamental design for a cosmetic brush set, as shown and described.

DESCRIPTION

FIG. 1 is a front side view of a cosmetic brush set (Excellence No. 3) showing the new design;

FIG. 2 is a back side view thereof;

FIG. 3 is a left side view thereof;

FIG. 4 is a right side view thereof;

FIG. 5 is a top view thereof;

FIG. 6 is a bottom view thereof;

FIG. 7 is a perspective view thereof; and,

FIG. 8 is an exploded view thereof.

The broken lines shown in drawings are for the purpose of illustrating portions of the cosmetic brush set and form no part of the claimed design.
